SHOCK RESISTANT CONTAINER

John K. M. Harrison, Gainesville, Va.

Application January 27, 1947, Serial No. 724,646

2 Claims. (Cl. 229—5.6)

1

This invention relates to containers and particularly to non-metallic containers of the type used for the packaging of liquids such as oils or foodstuff.

In the design of containers made of plastic, paper, or other non-metallic material, the principal problems presented are the maintenance of an adequate cost margin over metal containers together with the attainment of such objectives as mechanical strength, reliability in operation and adequate resistance against leakage of the liquid from the container. Toward the attainment of the foregoing objectives much effort has been expended and many forms of paper containers are now available in competition with metal containers of like capacity. With the advent of new liquid-proof plastic materials, the problem of leakage from non-metallic containers has been, to a large extent, solved. However, the problem of mechanical strength has not been heretofore solved in any manner consistent with the exigencies of the commercial situation.

It is therefore an object of this invention to provide a non-metallic container for the shipment and storage of liquid materials which is characterized by a simple and inexpensive type of construction and by very great resistance to mechanical shock.

It is contemplated, according to this invention, to provide a non-metallic container having a simply constructed end structure which renders the container resistant to rupture incident to rough handling and which tremendously increases the bursting strength of the container as a whole.

Other objects and advantages of the invention will be apparent upon consideration of the following detailed description of several embodiments thereof in conjunction with the annexed drawings wherein:

Figure 1 is a vertical sectional view of a tubular container constructed in accordance with the teachings of the present invention and embodying a novel end structure defining a shock absorbing zone at the ends of the storage space of the container;

Figure 2 is a detailed view similar to Figure 1 and illustrating a modified type of end structure with reference to but a single end of the container; and

Figure 3 is another view similar to Figure 2 but showing another modified type of construction.

Referring now in detail to Figure 1, the con-

2

tainer there illustrated is comprised of a tubular body portion 10 which may be made of paper laminae, plastic, or other suitable material. Each end of the body portion 10 is closed by a cup-like member 11 including a disc 12 and an integral, annular marginal flange 13. The dimensions of the cups 11 are so chosen with respect to the diameter of the body portion 10 that the cups may be inserted with the flanges 13 facing toward the respective ends of the body portion and, in that position, the flanges bear against the inner walls of the body portion. The cups are held in position by spinning over the ends of the body portion as shown at 14, the spun over portion gripping the ends of the annular flanges 13 and holding them tightly in the socket defined by the spun over portion.

During, or after, insertion of the cups 11, an adhesive may be employed to improve the frictional bond between the exterior surface of the flanges 13 and the interior surface of the body portion 10 against which they bear. In Figure 1 the adhesive is designated by the reference numeral 15 and is shown lying between the flanges 13 and the cylindrical walls of the body 10 adjacent its ends. It is apparent that the adhesive may be applied to the interior of the container 10 before the cups 12 are inserted or that it may be applied to the flanges 13 before they are inserted within the tubular body. Thermoplastic, thermosetting or other known adhesives may be used so long as they are resistant to the particular material which is to be placed in the container. A fillet may be built around the annular zone adjacent the plane of the discs 12 to assist in bonding the cups 11 in position and to assist in rendering the container as a whole leak-proof in the manner taught in Patents 2,106,738 and 2,173,585. After the cups 11 have been inserted, inverted cups 16 are applied to the ends of the container. The cups 16 each include a disc 17 and an integral, annular flange 18. While the cups 11 are inserted with the annular flanges facing toward the ends of the container and away from each other, the cups 16 are inserted in the opposite sense with the flanges facing toward the center of the container and toward each other. Because the flanges 13 and 18 extend in opposite directions from their respective discs, they mutually telescope and thus reinforce the cylindrical walls of the container in an annular zone adjacent each end. The flange 18 may rest upon the outer surface of the disc 12 as shown, or may be somewhat spaced therefrom. Upon ref-

erence to Figure 1 it can be seen that adjacent each end of the container the over-all side wall consists of the body wall, the flange 13, and the flange 18. Furthermore, the discs 12 and 17, being spaced apart by the respective flanges 13 and 18, define between them a generally cylindrical air space which materially contributes to the shock resisting properties of the container as a whole. It has been found that resistance to shock is somewhat enhanced if the inner edge of flange 18 is somewhat spaced from the disc 12 so that the cup 16 may function under shock conditions somewhat in the manner of a floating piston.

In Figure 1 the end structure as illustrated involves the use of an adhesive between the flanges 13 and the container wall, while the flanges 18 are frictionally held. In Figure 3, however, there is illustrated an alternative form of the invention in which the flanges 18 are held by an adhesive 19, while the flanges 13 are frictionally held. It will be understood that various combinations of the forms shown in Figures 1 and 3 may be used and that either or both cups 14 and 16 may be frictionally held or held by adhesives, and that adhesives may be used at one end of the container while a frictional arrangement is used at the other end thereof, the important feature of the construction being that the flanges of the cups face each other and telescope in such a way as to reinforce the ends of the container while the discs define between themselves a shock absorbing zone or air space.

While in Figure 1 the inner cup 14 is shown as attached by an adhesive to the walls of the container and also held by deformation of the ends of those walls, see spun over portions 14, it is apparent that either the adhesive alone or the spun over arrangement alone may be employed. It is contemplated that container liners in the form of thermoplastic films may be used or that thermoplastic films may themselves be used as adhesives.

In Figure 2 there is shown a further modified form of the invention in which the inner disc is of a transparent plastic material 20 having marginal portions 21 and a separable annular flange 22. In this case, the adhesive is placed between the margins 21 of the disc 20 and the inner side walls of the body portion 23, and the annular flange is used to impart rigidity to the marginal portions of the disc and to receive the spun over portion 24 of the end of the body portion 23. In this case, the outer cup is frictionally held, as shown in Figure 1, and consists of an annular flange 25 and a disc portion 26 integral therewith. It is contemplated that the form of the invention shown in Figure 2 will be particularly useful in the packaging of foodstuff since the outer cup, consisting of disc 26 and its flange 25, can be pried loose from the end of the container and visual access to the contents of the container may be had through the transparent disc 20. Furthermore, after the disc 20 has been punctured and access to the contents of the container has been gained, it is apparent that the outer cup may be replaced to constitute a temporary closure. This is particularly useful in the case

of foods which require refrigeration, it being apparent that the outer cup may function as an icebox cover in such cases. From the point of view of mechanical strength the form of the invention shown in Figure 2 affords the same advantages as those described above in connection with Figure 1; again there are two spaced discs defining between them a cylindrical air space, and again there are three side wall laminae of substantial thickness adjacent the ends of the container. While the disc 20 has been described as of transparent material, it is to be understood that parchment or other translucent or opaque material either rigid or flexible but of adequate mechanical strength may be used in lieu of a transparent plastic. It will be understood that the form of the invention shown in Figure 2 may be used at one end of the container, while at the other end of the container an end structure such as shown in Figures 1 or 3 may be employed, or that, if desired, the structure of Figure 2 can be used at both ends of the container. Should the disc 20 be comprised of a thermoplastic film, it is understood that the marginal portions of the film itself may be used to effect a bond between it and the container wall and the flange 25.

While the invention has been described with reference to but a few specific embodiments, it is apparent that considerable variation in structure and materials of construction is possible within the scope of the invention.

What is claimed is:

1. A container having a first closure wall within said container but spaced from the end of said container, a first flange extending from said first wall to the end of said container, the end of the container having a portion folded over and enclosing a part of said first flange, and a second closure wall across said end of the container and lying flush therewith, said second wall having a second flange extending toward said first wall and engaging and being complementary in configuration to said folded over portion of said container end and the unenclosed portion of said first flange, said first and second closure walls being of non-metallic flexible material and spaced to define a shock resistant zone.

2. A container as defined by claim 1 wherein said folded over portion of the end of said container is adhesively bonded to said part of said first flange.

JOHN K. M. HARRISON.
